POCKET CONTAINER FOR PIPE TOBACCO

Filed April 11, 1949

UNITED STATES PATENT OFFICE

2,571,714

POCKET CONTAINER FOR PIPE TOBACCO

John Henchert, Chicago, Ill., assignor to Continental Can Company, Inc., New York, N. Y., a corporation of New York

Application April 11, 1949, Serial No. 86,682

1 Claim. (Cl. 220—31)

1

The invention relates to new and useful improvements in a metal container for pipe tobacco which is especially adapted for pocket use. In this type of container, the body has parallel walls which are joined by semi-circular end walls. The closure has a central depression fitting within the container body and a depending peripheral flange forming an annular channel adapted to receive the upper end portion of the body.

An object of the invention is to provide a simple form of hinge for joining the closure to the body wherein one hinge part is formed from an integral part of the body blank, and the other hinge part is formed from an integral part of the closure blank.

A further object of the invention is to provide a hinge of the above type including a pintle and a strap wherein the pintle is an integral part of the closure and the strap is an integral part of the body and passes through a slot in the peripheral flange of the closure and extends about the pintle.

In the drawings:

Figure 1 is a top plan view of the improved container with the cover turned to open position;

Figure 2 is a rear side view of the container with the cover in closed position;

Figure 3 is a sectional view on the line 3, 3 of Figure 2;

Figure 4 is a sectional view on the line 4, 4 of Figure 2;

Figure 5 is a perspective view of a portion of the closure showing the bead on the periphery thereof and the manner of forming the pintle of the hinge structure; and

Figure 6 is a perspective view of the body and showing the manner of forming the strap which is to encircle the pintle on the closure member.

The improved pocket container includes a body portion having flat side walls 1, 1, which are joined by semi-circular end walls 2, 2. The body is made from a single blank which is bent to shape and the edges of the blank are joined by a side seam indicated at 3. The body wall at the upper end thereof is bent outwardly thence downwardly and flat against the outer surface of the body wall, as indicated at 4, 4. The closure for the body is formed from a single blank which is shaped to conform to the general shape of the body of the container. Said closure is indicated at 5, and is depressed so as to provide an annular wall 6 which fits within the body portion. In the drawings these parts are shown as separated for the purpose of illustration, but in practice there is a fairly close frictional fit between the

2

wall 6 and the inner face of the body wall of the container.

The closure member also has a peripheral flange 7 which is spaced from the vertical wall 6. At one flat side of the closure this flange 7 is rolled inwardly and upwardly to form a closed bead 8, which gradually merges with the peripheral flange 7 which extends around the remainder of the closure.

At two locations along the beaded portion of the closure, the closure is slit along lines 10—10, and along line 11, between the slits 10—10. The portions which are slit are rolled about the bead 8, as indicated at 12, in Figure 5, to form two circular pintles which are integral with the closure and are of larger diameter than the closed bead 8.

The depending flange 7 extends around the front and side walls of the closure and this flange is spaced from the vertical wall 6 so as to provide an annular channel which receives the upper end portion of the body as indicated in Figure 3.

There are two hinges for joining the closure to the body of the container. These are indicated as a whole at 9, 9. These hinges are similar in construction and the description of one will answer for the other.

The other part of the hinge is in the form of a hinge strap 13. The outwardly turned portion 4 of the body wall is cut along the lines 14, 14, and from the cut out portion the integral strap 13 is formed. This strap extends up through the opening between the portion 12 and the vertical wall 6 of the closure and then it extends over and around the pintle 12. This joins the closure to the body of the container. When the cover is raised it is the integral pintle carried thereby that turns in the hinge strap.

From the above it will be noted that a very simple form of hinge structure is produced which includes a pintle integral with the blank forming the closure and a strap integral with the body. When the closure is cut and the cut out portion rolled around the closed bead at the lower edge of the flange of the closure, this forms a very strong and durable pintle around which the hinge strap is placed. This enlarged pintle provides a hinge structure wherein the parts readily turn one on the other and it also provides a pintle which can be formed as an integral part of the closure structure.

It is obvious that minor changes in the details of construction can be made without departing from the spirit of the invention as set forth in the appended claim.

I claim:

A metal container comprising a body having flat side walls joined by semi-circular end walls, the upper end portion of the body being turned outwardly and downwardly flat against the body wall, a closure having a central depression fitting within said body and a peripheral flange extending down over the body wall when in closed position, said flange at one of the side walls having an inwardly rolled bead at its lower edge and 10 hinges for connecting said closure to said body, each hinge including a pintle formed from a portion of the bead and the flange cut above the bead, the cut portion of the flange being rolled around the bead to provide the pintle and a slot 15 in the flange, and a hinge strap formed from the outwardly turned portion of the body wall extending through the slot and around the pintle

5

for connecting the closure to the body so that the axis of the hinge will lie adjacent the upper edge of the body portion.

JOHN HENCHERT.
